UNITED STATES PATENT OFFICE.

HARRY A. THOMAS, OF PITTSBURGH, PENNSYLVANIA, ASSIGNOR TO MARGERIE THOMAS, OF PITTSBURGH, PENNSYLVANIA.

SHEET-METAL CONSTRUCTION.

1,347,190.

Specification of Letters Patent. Patented July 20, 1920.

Application filed November 3, 1919. Serial No. 335,290.

To all whom it may concern:

Be it known that I, HARRY A. THOMAS, a citizen of the United States, residing at Pittsburgh, in the county of Allegheny and State of Pennsylvania, have invented certain new and useful Improvements in Sheet-Metal Construction, of which the following is a specification.

My invention relates to the formation of sheet metal shapes, and is an improvement in the method of bending a continuous strip of sheet metal to provide a formed shape for use in building operations.

It has in view particularly to provide, in a formed sheet or strip, a main substantially plane or flat base with a flattened double rib extending slightly away therefrom in the same general plane, with an intervening space, for the reception of an intervening co-acting member, in the formation of a hammered joint, in roofing or other similar sheet metal work.

Generally stated, the invention consists in treating or operating on a strip of sheet metal by and through a series of successively advancing bending or pressing steps, through operative mechanism, whereby to gradually change the plane shape of the blank to the desired form by continuous operation on the blank through a series of steps or treatments, as hereinafter described.

In the drawings,

Figure 1 is a view in elevation of a series of pairs of rolls arranged for the carrying out of the several successive operative steps;

Fig. 2 is an inclusive view comprising the series of said rolls as to their groove formation;

Fig. 3 is an inclusive view of the cross sectional construction of the blank at points corresponding to each of the several roll treatments throughout;

Fig. 4 is a vertical sectional view on the line IV—IV of Fig. 1;

Fig. 5 is a similar view on the line V—V of Fig. 1;

Fig. 6 is an enlarged cross sectional detail view showing the blank in its finished form ready for connection with another co-acting sheet metal member; and

Fig. 7 is a cross sectional view showing the two parts in connected operative position.

In carrying out my invention I utilize a series of pairs of rolls $a-a$, $b-b$, $c-c$, $d-d$,

$e-e$, $f-f$, $g-g$, and $h-h$, mounted by their carrying spindles 2 and 3 respectively in suitable bearings in a housing frame 4 of proper construction. Spindles 2 and 3 are driven in opposite directions by intermeshing gearing 5—5 and driving gearing 6 of any suitable form. One of the spindles as 2, is mounted in a journal box 7 having a temper screw 8 for adjustment of one of the rolls, as a with relation to its other co-acting roll, so as to accurately locate the rolls with the necessary intervening pass.

As shown, the contour of the several sets of rolls is such as to gradually change the cross section of the flat blank, as clearly indicated in Fig. 3, through the several steps of operation, the first of which forms the comparatively shallow V-shaped depression a' in the blank. The second operation further bends the blank to provide the deeper depression and more abrupt shoulder b' , which treatment is carried still further in the third step, as indicated at c' . The fourth pair of rolls is so constructed, as shown, as to form the blank with a right angled shoulder, as indicated at d' . The fifth and sixth operations carry forward the bending operation so as to change the right angled shouleder form to successively accentuated Z shapes, as indicated at e' and f' respectively. The rolls $e-e$ and $f-f$ for these two operations are preferably located as to their mounting and operation at right angles to the previous rolls $a-a$, $b-b$, $c-c$, and $d-d$, so that the blank in passing between them is treated in the easiest and most convenient way. After passing between rolls $f-f$, the metal has been bent into an accentuated Z form, the operation drawing the sides together, and it is now ready to be flattened down to provide the reversed double rib formation, as indicated at g' . This is done between the flat faced rolls $g-g$ mounted in the same manner as rolls a to d , rolls $g-g$ being placed sufficiently far apart so as to press the metal together with ample intervening space between the several thicknesses, as clearly shown. The corners of the rolls are rounded or filleted as shown, either convex or concave, so as to insure the final rounded bends of the finished product, as shown at g' , h' , Fig. 3.

The final step of the operation, which is to bring the two plane edges into alinement, and at one side of the double and flattened

parallel rib, is accomplished by rolls $h-h$, one of which is centrally channelled as indicated, the other being plane. The centrally channelled roll is depressed at its middle portion just sufficient to provide clearance for the projecting bend over flattened rib or hook of the final construction, and the terminals of the roll, co-acting with the plane faced other roll, force the metal into the desired position and shape, as indicated at h' .

These several steps of operation are carried out continuously and in a long blank all at the same time, *i. e.*, the final step being operated upon the advancing end of the blank while the first step is being operated on the trailing end of the blank, so that it emerges finally from the simultaneously operating steps in finished form.

In Fig. 6 I show the final form of the blank in position ready for attachment and connection with the co-acting member 9, having the right angled leg 10 which is inserted in the space 11 between the parallel double rib member 12 and the main back 13. The terminal 14 of said back is then bent over at right angled position, as indicated, in the manner of the "hammer joint" above referred to, whereby the two parts are firmly attached together and a permanent water proof joint is provided.

The resulting construction, due to the integral formation of the main blank, its facility for connection with the supplemental sheet, the absence of any excessive rupturing strains in the gradually changing several steps, the speed of operation, economy of construction, and general advantages of the invention, are features of im-

portance and novelty in the art, and greatly contribute to the efficiency and desirability of the operation.

It will be understood that the degree of deflection at each various step, the specific cross section of the shape and various other features of detail construction as to the mechanism utilized, or in other respects, may be changed or varied by the skilled mechanic, but that all such changes are to be considered as within the scope of the following claims.

What I claim is:

1. In the formation of a sheet metal joint member, the gradual deflection of a flat blank by a series of simultaneously operating continuous rolling treatments of a movable blank to provide first a V-shaped groove, then a right angled shoulder, then an acutely reversed Z formation with rounded corners, and then flattening the offset double rib thus formed to parallelism with the main blank with intervening clearance.

2. In the formation of a sheet metal joint member, the gradual deflection of a flat blank by a series of simultaneously operating continuous rolling treatments of a movable blank to provide first a V-shaped groove, then a right angled shoulder, then an acutely reversed Z formation with rounded corners, and then flattening the offset double rib thus formed to parallelism with the main blank with intervening clearance, and then further bending one side of the blank to parallelism with the other side.

In testimony whereof I hereunto affix my signature.

HARRY A. THOMAS.
